FUEL OIL FILLING SYSTEM

Francis L. Boylan, New Orleans, La.

Application August 13, 1945, Serial No. 610,495

4 Claims. (Cl. 137—68)

1

The present invention is an improvement on the Fuel oil filling system disclosed in the patent to McCauley et al., Patent No. 2,340,070, granted January 25, 1944.

In the system disclosed in the aforesaid patent, it has been discovered that when all the tanks become full and the last of the manifold valves are closed, that the stand pipe valve will automatically close, and that the closing of the stand pipe valve will cause the full pressure of the fuel oil pump to be developed on the filling line and filling connections with no flow in the filling line or connections. Unless the pumps are stopped immediately, the filling connections may become broken to spill fuel oil over the deck and create a serious fire hazard.

The present improvement has for an object to provide a means for assuring that the stand pipe will remain open when all the tanks are full and all the manifold valves are closed to prevent the building up of full pump pressure on the filling lines and filling connections.

Another object of the present invention is to provide a means responsive to the full condition of all the tanks to prevent the standpipe valve from automatically closing when the last of the manifold valves are closed.

A still other object of the invention is to provide a means responsive to the closing of all the manifold valves for preventing the standpipe valve from automatically closing when the last manifold valve is closed.

Figure #1 is a diagrammatic view of one embodiment of the invention in which a means responsive to the full condition of all the tanks is utilized to prevent the standpipe valve from automatically closing when the last manifold valve is closed.

Figure #2 is a diagrammatic view of another embodiment of the invention in which a means responsive to the closing of all the valves prevents the standpipe valve from automatically closing when the last manifold valve is closed.

The Fuel oil filling system of the patent to McCauley et al. No. 2,340,070, provides for the simultaneous filling of a plurality of fuel oil tanks on a vessel. The tanks have various shapes and capacities and will become full at different times. The system provided is arranged with a standpipe valve in a standpipe which will automatically open when any one of the tanks become full to reduce the pressure in the filling lines and connection. When the manifold valve to the full tank is closed, the standpipe valve will automatically close to re-establish the full pump pressure in the filling lines and connections. This automatic closing operation of the standpipe valve takes place at the instant when each manifold valve is closed. If the tanks are all full and the last manifold valve is closed, the standpipe valve

2

will be closed and the pump pressure will be re-established on the filling lines and connection which may build up to such pressure as to cause a rupture of the filling lines or connections. To prevent the closing of the standpipe valve when this condition exists and thus guard against spilling fuel oil over the decks and creating a fire hazard, is the purpose of the present improvement.

10 In Figures #1 and #2, a standpipe 1 is provided with a valve 2 capable of opening the standpipe for diverting the flow of fuel oil temporarily and capable of being closed to stop such diversion of the fuel oil so that the full pump pressure will again be developed in the fuel oil filling lines. The valve 2 is provided with a combined valve closing motor, clutch and spring operated opening means 3 for actuating the standpipe valve in response to the control of an electrical system 20 to be later described. The means 3 is arranged so that when it is energized, the valve will be closed and when the circuit and the means 3 connected thereto is de-energized, the valve will automatically open.

For controlling the means 3, a differential relay 4 is provided for each tank, having a coil 5 connected at one end to the negative side of an electric supply circuit 6. A connection is made to the coil at a point intermediate its ends to the 25 positive side of the electric supply circuit 7, whereby a current will continually be flowing in the one part of the coil 5. The other end of the coil 5 is connected through a switch means 8 associated with the manifold valve leading to the 30 particular tank and through another switch means 9 to the negative side of the electrical supply circuit 6. The switch means 8 is normally closed while the manifold valve is open. The switch means 9 is normally closed and is associated with a pressure responsive means 10 in 35 the tank that opens the switch 9 when the tank becomes full. While the switches 8 and 9 remain closed, an electric current will flow in the two parts of the differential relay coil 5, and it will 40 be electromagnetically balanced. The differential relay 4 has a contactor associated therewith shown at 11, which is normally closed while the differential relay coil 5 is balanced. The switches 11 of each relay are connected in series between 45 the positive side of the electrical supply circuit 7 through a relay coil 12 to the negative side of the electrical supply circuit 6. The relay coil 12 controls the supply of electrical power to the valve actuating means 3 through a normally 50 closed contactor 13 of the relay 12 and a normally closed contactor 14 of the relay 15. While this 55 circuit is closed or completed, the valve 2 will be closed and will be maintained closed until the circuit becomes open.

60 The switch 11 is shunted by a normally open

switch 16 associated with the manifold valve of the particular tank. It will be readily understood that when a tank becomes full, the pressure responsive means 10 actuates the switch 9 to open the circuit through the lower part of the differential coil 5 to thus unbalance the coil 5 and cause the contactor 11 to be opened. This opens the circuit through the relay coil 12 and the contactor 13 opens the supply circuit to the means 3, causing the valve 2 to be opened. The valve 2 will remain open to divert the fuel oil and maintain a lower pressure on the fuel oil filling lines and connections until the manifold valve of the full tank has been closed. When the manifold valve to the full tank has been closed, the switch 16 associated therewith, will be closed to shunt the open contactor 11 and thus re-establish the circuit through the relay coil 12 to cause the contactor 13 to close the supply circuit through the switch 14 to the means 3. This results in a closing of the valve 2 and a re-establishment of the full pump pressure on the filling lines. Also, when the manifold valve is closed, the switch 8 opens to break the circuit to the switch 9, and thus maintains the differential coil 5 unbalanced. It may occur that the manifold valve is closed prior to the tank becoming full. In such instance, the circuit through the closed switch 9 would then be opened by the switch 8. This causes the switch 11 to be opened, and the switch 16 shunts the switch 11 to re-establish the circuit through the relay coil 12. The description so far, relates to the system as it is disclosed in the aforesaid patent, and which is partially disclosed in Figures #1 and #2.

Referring more particularly to Figure #1 of the drawing, the differential relay 4 is provided with an additional contactor 17 in series with a relay coil 15. The contactor 17 of each differential relay are connected in parallel between the positive side of the source of electric power 7 and a conductor 18 connected through the coil 15 to the negative side of source of power 6. The contactor is normally closed, while the differential relay remains balanced. When the relay 5 becomes unbalanced by reason of a tank becoming full or by reason of the manifold valve being closed, the contactor 17 will open. The circuit through the relay 15 remains completed, however, until all the switches 17 become opened. When all the switches 17 become opened by reason of all tanks becoming full or all manifold valves being closed, the circuit through the relay coil 15 will be interrupted and the contactor 14 opens the supply circuit to the means 3. It will thus be seen that the valve 2 will be opened when the last tank becomes full or all manifold valves are closed, and will be prevented from being closed when the last manifold valve is closed to shunt the last switch 11.

Referring to Figure #2, a slightly different method is used to open the circuit of the relays. A switch 19 is associated with the manifold valves and is normally closed while the manifold valves are open. The switches 19 are connected in parallel between the positive side of the supply circuit 7 and a conductor 18 connected through the relay coil 15 to the negative side of the supply circuit 6. When each manifold valve is closed, the switch 19 is opened. The circuit through the relay 15 remains closed however until the last manifold valve is closed at which time the last switch 19 is opened to open the circuit through the relay coil 15 and thus interrupt the supply circuit to

the means 3, at which time the valve is open and remains open when all manifold valves are closed.

Having described my invention and its mode of operation, what I desire to secure by Letters Patent is:

1. In a fuel oil filling system of the class described comprising, a plurality of tanks to be filled, a filling system for said tanks, including a manifold valve connecting each tank to said filling system, a stand-pipe connected to said filling system for diverting the flow of fuel oil, a stand-pipe valve in said stand-pipe, means for opening said stand-pipe valve when any one of said tanks become full for diverting the flow away from said full tank, means responsive to the closing of the manifold valve to said full tank for closing said stand-pipe valve, and means for preventing the closing of said stand-pipe valve when all the manifold valves are closed.
2. In a fuel oil filling system of the class described comprising, a plurality of tanks to be filled, a filling system for said tanks, a manifold valve for connecting and disconnecting each tank to said filling system, a stand-pipe connected to said filling system, a stand-pipe valve in said stand-pipe, means responsive to a full condition of any one of said tanks and operable to open said stand-pipe valve, means responsive to the closing of the manifold valve to said full tank and operable to close said stand-pipe valve and means responsive to the full condition of all tanks and operable to prevent the closing of said stand-pipe valve when the last of said manifold valves is closed.
3. In a fuel oil filling system of the class described comprising, a plurality of tanks to be filled, a filling system for said tanks, a manifold valve for connecting and disconnecting each of said tanks to said filling system, a stand-pipe connected to said filling system, a stand-pipe valve in said stand-pipe, means responsive to a full condition of any of said tanks and operable to open said stand-pipe valve, means responsive to the closing of the manifold valve to the full tank and operable for closing said stand-pipe valve, and means responsive to a full condition of all of said tanks and to the closing of all of said manifold valves and operable to prevent the closing of the stand-pipe valve when all of said manifold valves are closed.
4. In a fuel oil filling system of the class described, a plurality of tanks to be filled, a filling system for said tanks, a manifold valve for connecting and disconnecting each tank to the filling system, a stand-pipe connected to said filling system, a stand-pipe valve in said stand-pipe, means operable in response to a full condition of any one tank to open said stand-pipe valve, means operable in response to the closing of the manifold valve to the full tank to close said stand-pipe valve and means operable in response to a closed condition of all of said manifold valves to prevent the closing of said stand-pipe valve.
